TYPEWRITER ERASER

Emily S. Teters, 1213 SE. Bidwell St., Portland 2, Oreg., and Warren A. Aikins, 923 20th Ave., Longview, Wash., and William E. Strader, 803½ S. 3rd, Kelso, Wash.; said Aikins and Strader assignors to said Teters

Filed June 20, 1958, Ser. No. 743,316

9 Claims. (Cl. 197—181)

This invention relates to a power-operated eraser adapted to be driven by the motor of an electric typewriter or the like.

Objects of the invention are to provide a convenient power-operated eraser for use by typists and the like; to provide an eraser driven by the typewriter motor; to provide an eraser which may be withdrawn from an operating mechanism mounted on or inside the typewriter itself; to provide a novel and improved mechanism for operating the eraser when it is withdrawn for use and to provide an eraser which is attached to a typewriter so that it will always be conveniently available and ready for use when needed.

In the preferred embodiment illustrated in the drawing, the present eraser is driven by a flexible shaft wound on a spring reel to retract the shaft when the eraser is not in use. When the eraser is withdrawn for use the rotation of the reel engages a clutch with the typewriter motor to energize the flexible shaft and rotate the eraser. The flexible shaft may be energized from a separate motor if desired.

The invention will be better understood and additional objects and advantages will become apparent from the following description of the preferred embodiment illustrated in the accompanying drawing. It is to be understood, however, that various changes may be made in the construction and arrangement of parts and that certain features may be used without others without departing from the spirit of the invention and all such modifications within the scope of the appended claims are included in the invention.

In the drawing:

Figure 1 is a longitudinal sectional view showing the eraser and handle of the present device;

Figure 2 is a longitudinal sectional view of the flexible shaft reel and automatic clutch;

Figure 3 is a perspective view in phantom of a typewriter, showing the present device mounted on the outside of the typewriter casing;

Figure 4 is a bottom plan view of the typewriter showing the drive connection with the typewriter motor;

Figure 5 is a cross sectional view of the flexible shaft reel taken on the line 5—5 of Figure 2; and

Figure 6 is a cross sectional view taken on the line 6—6 of Figure 2.

Figures 3 and 4 show the present device mounted on the outside of a conventional typewriter. It is to be understood, however, that the device is not limited to use as an attachment since the operating mechanism may be contained within the typewriter frame instead of being mounted on the outside thereof. In Figure 3, the typewriter 10 has a side plate 11 which affords support for the reel housing 12. Extending from an opening 13 in the reel housing 12 is a flexible shaft 14 having a handle end 15 equipped with an eraser 16 for erasing mistakes made by the typist. The typewriter 10 is operated by an

2

electric motor 17. The motor 17 is provided with a shaft extension 18, if necessary, to connect with a drive shaft 19 extending to the housing 12.

Referring now to Figure 2, a reel support 20 is mounted on the outside of side plate 11 by means of screws 21. Reel support 20 has a boss 22 projecting inwardly through an opening in side plate 11 and equipped with a bearing 23 for the shaft 19. The end of shaft 19 is hollow to receive a clutch shaft 25 and clutch compression spring 26. Clutch shaft 25 is driven by a transverse pin 27 having limited longitudinal movement in a slot 28 in shaft 19. The outer end of clutch shaft 25 carries a male clutch cone 30.

Reel support 20 is cylindrical and equipped on its outer surface with a screw thread 31 which is engaged by an interior thread in the reel 32. Reel 32 has an end wall 33 supporting a bevel gear housing 35 by means of screws 36. Bevel gear housing 35 contains a bearing 37 for a stub shaft 38 having a female clutch cone 40 on its inner end concentric with male clutch cone 30. The outer end of shaft 38 is equipped with a bevel gear 41.

Bevel gear 41 drives a bevel gear 42 on a transverse stub shaft 43 journaled in the housing 35. One end of shaft 43 is hollow to receive flexible shaft 45 which, together with its tubular sheath 46, was referred to generally as flexible shaft 14 in Figure 3. Driving connection is established between stub shaft 43 and flexible shaft 45 by means of a setscrew 47 in the hub of bevel gear 42. The flexible shaft 14 comprising shaft portion 45 and sheath portion 46 extends through an opening 48 in the reel communicating with a continuous spiral groove 50 in the cutter surface of the reel. The reel 32 is tensioned to wind the flexible shaft into groove 50 by means of a coil spring 51 having an outer end 52 anchored in the reel support 20 and an inner end 53 anchored in the bevel gear housing 35.

In Figure 2, pin 27 bears against the right end of slot 28 to prevent clutch cone from engaging clutch cone 40, it being remembered that the typewriter motor runs continuously, causing clutch cone 30 to revolve continuously. When a predetermined length of flexible shaft 14 is withdrawn from reel 32, the screw thread 31 carries the reel to the left in Figure 2, bringing clutch cone 40 into engagement with the clutch cone 30 to drive the flexible shaft 45 within its stationary sheath 46. If a greater length of flexible shaft is withdrawn from the reel, the latter and clutch cone 40 will move further to the left on thread 31 causing the end of shaft 25 to compress spring 26 and move pin 27 away from the right end of slot 28 whereby the rotation of the reel is not limited by the engagement of the clutch.

When handle 15 is released, spring 51 rotates reel 32 to wind the flexible shaft back into groove 50, such rotation of the reel causing it to travel axially to the right on thread 31, disengaging clutch cone 40 from clutch cone 30. Thus, the flexible shaft is not driven after it has been reeled in beyond a predetermined length and the present device does not impose a load on the typewriter motor when the typewriter is in use.

Referring now to Figure 1, the handle 15 is a hollow tube containing bearings 58 and 59 for a hollow eraser tube 60 which is secured to the end of flexible shaft 45. The outer end of eraser tube 60 is split longitudinally and equipped with a slidable lock ring 61 to contract the tube into gripping engagement with the eraser. For this purpose, the segmental end of tube 60 may be slightly thickened or otherwise provided with ramp or wedging surfaces so that the end of the tube will be contracted by sliding the ring 61 downwardly. When lock ring 61 is released, the eraser is ejected by a compression ejection spring 62. The tube 60 and lock ring 61 constitute a

chuck which will also receive a rotary brush for cleaning the typewriter, if desired.

Having now described our invention and in what manner the same may be used, what we claim as new and desire to protect by Letters Patent is:

1. In a power-operated eraser and the like, a flexible shaft for driving the eraser, a reel receiving said flexible shaft when the eraser is not in use, and means operable by said reel to energize said flexible shaft when the flexible shaft is partially withdrawn from the reel.

2. In a power-operated eraser and the like, a flexible shaft for driving the eraser, a reel receiving said flexible shaft when the eraser is not in use, a spring for rotating the reel to wind the flexible shaft on the reel, and means for energizing said flexible shaft when it is partially withdrawn from the reel.

3. In a power-operated eraser and the like, a flexible shaft for operating the eraser, a reel receiving said flexible shaft when the eraser is not in use, a reel support having threaded engagement with the reel whereby the reel travels axially on said support in winding and unwinding said flexible shaft, means for rotating said reel to wind said flexible shaft thereon, and means operable by the axial movement of said reel on said support for energizing said flexible shaft.

4. In a power-operated eraser and the like, a flexible shaft for driving the eraser, a reel receiving said flexible shaft when the eraser is not in use, a source of power, and a clutch connected with said source of power operable by said reel to energize said flexible shaft.

5. In a power-operated eraser and the like, a flexible shaft for driving the eraser, a reel receiving said flexible shaft when the eraser is not in use, a driven clutch member carried by said reel and connected with said flexible shaft, a support for said reel, a driving clutch member carried by said support and connected with a source of power, and means operable by said reel for engaging said clutch members to drive said flexible shaft.

6. In a power-operated eraser and the like, a flexible shaft for driving the eraser, a reel receiving said flexible shaft when the eraser is not in use, a driven clutch member connected with said flexible shaft and mounted coaxially with the reel, a support for said reel having screw

10
15

threaded engagement therewith whereby the reel travels axially on said support in winding and unwinding said flexible shaft, a source of power, and a driving clutch member connected with said source of power and mounted in said support coaxially with said reel and in cooperative relation with said driven clutch member so that axial movement of the reel in unwinding said flexible shaft carries the driven clutch member into engagement with the driving clutch member for driving said flexible shaft.

7. In an electric typewriter having an electric motor for operating the typewriting mechanism, a clutch member operable by said motor, an eraser driven by a flexible shaft, a reel receiving said flexible shaft when the eraser is not in use, a clutch member connected with said flexible shaft, and means operable by rotation of said reel for engaging said clutch members.

8. In an electric typewriter having an electric motor for operating the typewriting mechanism, a reel support, a clutch member in said reel support driven by said motor, a reel on said reel support, a clutch member on said reel engageable with said first clutch member by rotation of said reel, a flexible shaft on said reel connected with said second clutch member, and an eraser driven by said flexible shaft.

9. In a typewriter having an electric motor for operating the typewriting mechanism, a clutch driven by said motor, an eraser having flexible drive means from said clutch, said eraser having universal movement to different erasing positions to suit the convenience of the operator, means movable in advancing or return directions to allow movement of the eraser to erasing position and to retract said eraser, and means actuated by said movable means when moved in said advancing and return directions to respectively engage and disengage said clutch.
